UNITED STATES PATENT OFFICE.

HARRY M. GRIFFIN, OF BRADFORD, VERMONT.

GARMENT-SUPPORTER.

SPECIFICATION forming part of Letters Patent No. 430,640, dated June 24, 1890.

Application filed January 4, 1890. Serial No. 335,881. (No model.)

To all whom it may concern:

Be it known that I, HARRY M. GRIFFIN, a citizen of the United States, residing at Bradford, in the county of Orange and State of Vermont, have invented certain new and useful Improvements in Garment-Supporters; and I do declare the following to be a full, clear, and exact description of the invention, such as will enable others skilled in the art to 5
10 which it appertains to make and use the same, reference being had to the accompanying drawings, and to the letters of reference marked thereon, which form a part of this specification.

15 My invention relates to certain new and useful improvements in garment-supporters, and the nature of the same will be understood from the following description and claims, when taken in connection with the accompanying drawings, in which latter—

20 Figure 1 is a view in perspective of the device complete; Fig. 2, a cross-section through the same, and Fig. 3 a view in detail of the blank from which the body or main portion 25 of the device is formed.

In the drawings, A represents a blank from 30 which the body or main portion of the device is formed, the shape of such blank being clearly shown in Fig. 3 of the drawings, 35 wherein it is represented as being oblong and provided at each end with a cross-piece, (marked *a a'*, respectively.) What may be called the "top" or "forward" end of the blank (that end which is provided with the cross-piece *a*) is curved upwardly and then back toward the body of the blank, the opposite ends of the cross-piece *a* being bent toward each other to form catches *b*, with which the locking ends of a pin *B* engage. The lower 40 or rear end of the blank is curved downwardly and then bent back upon the body of the blank, the ends of cross-piece *a'* being bent across the blank until they rest thereupon, their ends meeting. This end of the 45 blank in being bent as described forms a bearing for the pin *B*, which pin consists of a single piece of suitable spring metal bent at its center to form part *c*, which serves as a pivot for such pin, the part *c* resting in the 50 bearing formed by the bend in the rear end of the blank. The two arms of the pin thus formed are then bent at substantially right

angles to such part *c*, and again bent to form the locking-arms *d*, the latter at their forward or upper ends engaging the catches *b*. 55

C represents a hook, which consists of a wire bent to the form shown, the ends of the wire encircling the part *A*, the hook being preferably formed of spring metal, which will allow of the ready detachment of the hook. 60

The manner of using the device is as follows: Supposing the locking ends of the pin to be in engagement with the catches *b* to disengage them, the points of the pin are pressed toward each other until they are carried beyond the catches, after which the pin is turned on its pivot. The points of the pin are then passed through the garment to be supported—such as men's drawers—and the points again engaged with the catches, the 70 hook *C* occupying the position shown in Fig. 1. The hook *C* is then slipped over the upper edge of the trousers-band and the drawers supported.

It will be understood that I do not wish to 75 confine myself to the use of the device in connection with drawers, but desire to use the same in the many ways for which it is adapted.

The lower part of the blank is bent over to form a cylindrical bearing for the pin, and 80 the ends of cross-piece are then bent over the blank, closing and strengthening said bearing. When the hook is disconnected, the pin portion may be used as a garment-supporter after the usual manner of a safety-pin; or by 85 passing the pin through both the top of the drawers and pantaloons the drawers will be supported. By inserting the pin in the drawers and attaching the spring-hook to the pin portion the drawers may be supported by 90 simply passing the hook over the top of the pantaloons, said hook accommodating itself to the different positions of the body, which a rigid hook will not do. If a button is lost off the pantaloons, by attaching the pin to the 95 latter the loose hook will act as a button for the suspenders; or the pin may be passed through the top of both the drawers and pantaloons, and the whole device will act as both drawers-supporter and suspender-button. 100

What I claim is—

1. A garment-supporter having a double-pin and a body portion with its lower end bent to form a bearing for the said pin, and

provided with laterally-projecting ears, the body portion bent back upon itself and the ears bent over said body portion to strengthen the bearing and securely hold the said pin 5 therein, the upper end of the said body portion provided with laterally-projecting ears bent to form catches for the pin, substantially as described.

2. A garment-supporter having a pin and 10 a body portion with its lower end bent to form a cylindrical bearing for the pin, and provided with a cross-piece bent over said

body portion to strengthen the bearing and securely hold the pin therein, the upper end of said body portion being bent to form 15 catches for the pin, and a spring-hook detachably connected to said garment-supporter, substantially as described.

In testimony whereof I affix my signature in presence of two witnesses.

HARRY M. GRIFFIN.
